SUCTION CLEANER

Ralph C. Osborn, Bloomington, Ill., assignor to
 Eureka Williams Corporation, Detroit, Mich., a
 corporation of Michigan

Application April 8, 1947, Serial No. 740,018

12 Claims. (Cl. 183—37)

1

This invention relates to vacuum cleaners and has particular relation to tank type vacuum cleaners having handles and cleaner tools by which a tank may be pulled or moved around the room by the operator.

In such type cleaners it has been the custom heretofore to provide various kinds of vents associated principally with the wand or cleaning tools attached to the air hose through which air may be admitted continuously to the cleaner for cooling the cleaner motor at all times and regardless of the fact that the cleaning tool is being used in such manner that very little air is otherwise admitted. This method of cooling the motor has been found objectionable for the reason that such air vents sometimes cause whistling noises which are objectionable and in any event do not provide the air for cooling the motor in the event the air hose, dust separator or the tank outlet should become obstructed to such an extent as to prevent the flow of air through the tank.

It is now proposed to provide the tank with conduit means adapted for the admission of air directly to the tank for cooling the motor.

In the various embodiments of the invention shown in the drawings it is proposed to admit air directly to the suction side of the tank by recirculating some of the air in the tank from the discharge to the suction side thereof, and this admission of air is capable of control by the operator by any of the various means shown for several different purposes.

An object of the invention is to provide for cooling the motor by the admission of air directly to the suction side of the tank and to provide means for controlling this admission if desired, either automatically or manually, to any desired extent.

Another object of the invention is to provide a means for modulating the suction of a suction cleaner so as to make it possible to obtain the most efficient operation of various suction cleaning tools.

Other and further objects of the invention will be apparent by reference to the accompanying drawings of which there are two sheets, which, by way of illustration, show preferred embodiments and the principles thereof and what I now consider to be the best mode in which I have contemplated applying these principles. Other embodiments of the invention embodying the same or equivalent principles may be used and structural changes may be made as desired by those skilled in the art without departing

from the present invention and the purview of the appended claims. I also contemplate that of the several different features of my invention, certain ones thereof may be advantageously employed in some applications separate and apart from the remainder of the features.

In the drawings:

Fig. 1 is a side elevational view with a portion thereof in vertical cross section of a tank cleaner embodying one form of the invention;

Fig. 2 is an end elevational view of a tank cleaner handle embodying another form of the invention, as this handle might be seen in the plane of line 2—2 when employed on the tank illustrated in Fig. 1;

Fig. 3 is a vertical sectional view through the handle illustrated by Fig. 2, taken substantially in the plane of line 3—3 in Fig. 2;

Fig. 4 is a fragmentary view of a portion of the handle shown by Fig. 3 illustrating the valve mechanism thereof in a different operative position;

Fig. 5 is a vertical sectional view of a cleaner handle illustrating another form of the invention;

Fig. 6 is a fragmentary view of the handle shown by Fig. 5 with the valve mechanism thereof in a different position;

Fig. 7 is a plan view partly in cross section showing a portion of the handle illustrated by Figs. 2, 3 and 4, taken substantially in the plane of line 7—7 in Fig. 3; and

Fig. 8 is a perspective view of the operating knob of the handle illustrated by Figs. 5 and 6.

Referring to Fig. 1 the numeral 10 indicates a cylindrical tank supported at one end by a pair of wheels 11 and at the other end by a sliding support 12. The two ends of the tank are closed by end bells 13 and 14, the former being provided with a discharge opening 16 and the latter with a flexible air hose 17 through which air is admitted to the tank 10. The hose 17 may be any desired length and may have attached thereto the usual operating wand to which cleaning tools of various kinds may be attached. The discharge opening 16 is constructed in any suitable manner so that a hose may also be attached thereto if desired, and in connection with which various kinds of pressure tools and devices may be employed.

The tank 10 is divided internally thereof into a suction compartment 18 and discharge compartment 19, this being accomplished by providing a wall formed by placing a fan 21 adjacent the central portion of the tank and sealing the outside of the fan to the inside of the tank by a rub-

ber support and sealing ring 22. The ring 22 also provides for absorbing vibration resulting from the operation of the fan. The fan 21 is located inside a casing 23 having an inlet opening 24 adapted to admit air to the fan from the suction compartment 18 of the casing 10. The opposite or discharge end 26 of the casing 23 supports an electric motor 27 for the fan 21, the motor 27 having a casing or frame 28 secured to the fan casing 23 in such manner that the air discharged from the fan casing is circulated through and/or over the motor for cooling the same. The motor casing is provided with an outlet opening 29 through which air escapes into discharge compartment.

The suction compartment 18 of the casing 10 is provided with a bag or dust separator 31 having the open end thereof attached to the tank 10 and the end bell 14 in such manner as to receive internally thereof the air discharged by the hose 17. The dust separator 31 receives such air, cleans the dirt therefrom and discharges the air so cleaned into the suction compartment 18 of the tank 10.

In order to be able to lift the tank and to carry the same about, the casing 10 is provided with a handle 32 extending longitudinally along the upper portion thereof in such manner that the tank will balance properly when carried by the handle. In such position it will be observed that one end of the handle is adjacent the discharge compartment in the casing 10 while the other is adjacent the suction compartment thereof. In order to provide means for recirculating a small quantity of air within the tank from the discharge to the suction side thereof, the handle 32 is provided with a conduit 33 extending from one end to the other of the handle, and this conduit communicates with the discharge compartment 19 and the suction compartment 18 through openings in the casing 10 indicated at 34 and 36 respectively. It will be noted that the openings 34 and 36, and particularly opening 36, somewhat restrict the flow of air through the conduit 33 so that only a small quantity of air may pass therethrough in any event. This restriction is provided so that in the event the separator 31 is clean and there is no unusual restriction in the hose 17 or any of the tools employed with the cleaner, very little air will tend to flow through the conduit 33. The fact that some air will flow through in all events does not particularly affect the normal operation of the cleaner, inasmuch as practically all cleaning tools are provided with openings or vents to by-pass some air through the cleaning tool so that the latter may be easily moved. In normal operation the fan 21 simply receives air and discharges the same through and around the motor 27 and from whence it leaves the discharge compartment 19 through the opening 16.

However, in the event the cleaning tool employed, the hose 17, the dust separator 31 or the discharge opening 16 (or any of the pressure tools employed with the latter), become restricted so that the normal or predetermined amount of air does not flow through the cleaner, then notwithstanding the restriction provided by the openings 34 and 36 and the conduit 33, some of the air will be recirculated in the tank, and this will be sufficient in all events to cool the motor 27 and to keep the latter from burning out.

Referring now to Figs. 2, 3, 4 and 8, it will be noted that the handle 32 may be provided with a valve 38 for controlling the flow of air through

the conduit 33. To receive the valve 38 the conduit 33 is modified adjacent the opening 36 in the tank casing 10 in such manner as to provide a valve seat opening 39, a valve stem opening 41 and a valve operating mechanism compartment 42. The valve head is indicated at 43 and the valve stem at 44. The stem 44 is provided with a transversely disposed pin 46 against which a washer or collar 48 is adapted to be supported against the compressive force of a spring 49. The opposite end of the spring 49 is supported upon the lower end of the compartment 42. It will be noted that the stem 44 is smaller than the opening 41 so as to permit the flow of air through the opening 41 around the stem when the valve head 43 is away from the seat 39.

It will be noted in Fig. 3 that the valve head 43 is shown in two positions: being shown in one position in dot and dash lines in which the head 43 is off its seat and in another position in full lines in which the head is seated or closed. It will be apparent from the structure disclosed that the valve 38 will normally be resiliently closed by the spring 49. However in the event the pressure in the suction compartment 18 becomes abnormally low or that in the discharge compartment 19 becomes abnormally high, as might occur in the events previously described, the valve 38 will open, thus allowing air to be recirculated from the discharge to the suction compartments of the tank through the conduit 33 and the various passages associated with the valve 38.

Under certain circumstances it is desirable to have the conduit 33 remain closed in all events so that no air can be recirculated from the discharge to the suction compartments of the tank casing 10. Such circumstances would occur when the tank might be used as a pressure device as when various kinds of spraying, drying or other pressure tools might be employed in connection with a hose attached to the discharge opening 16. To provide for such contingency the upper end of the valve stem 44 is reduced in cross section to provide an annular groove indicated at 51, this groove being adapted to be operatively associated with the edge of an opening 52 formed in a transversely disposed bar 53. The opening 52 (see Fig. 7) is formed in such manner as to provide two passages, one large enough to permit the free vertical movement of the valve stem 44 when the bar is in the retracted position shown in Figs. 3 and 7 and the other small enough to limit the movement of the stem when the bar is in the forward position indicated by Fig. 4. In the latter position, as is shown by Fig. 4, the valve head 43 is disposed against its seat 39 in such manner as to prevent the flow of any air through the conduit 33.

The bar 53 is supported in the aforesaid position in a horizontally disposed slot in the handle 32 indicated by the numeral 54, the rear end of the slot being provided with an enlarged opening 55, the upper end of which is exposed to the upper part of the handle 32. In the opening 55 there is located a button or knob 56 attached to the rear end of the bar 53 by which the bar may be moved from its retracted to its forward position at the will of the operator.

It will be noted from Fig. 4 that in the forward position the bar 53 extends outwardly a short distance beyond the end of the handle 32. This outwardly extending end may be marked in such manner as to indicate that the valve 38 is in the off or inoperative position. This may be done by painting or coloring the end of the

bar red or some other suitable color, or, as is shown in Fig. 7, displaying the word "Off" on the exposed portion thereof. Also, as may be seen from Fig. 7, the bar in its retracted position will be located entirely within the opening 54 so that the end thereof may not be seen.

It will be apparent from the modification shown by Figs. 2, 3, 4 and 7 that the valve 38 may be operated automatically in response to the difference in pressure between the discharge and the suction compartments or the valve 38 may be rendered operative to close the conduit 33 entirely by operating the button 56 to move the bar 53 to the outward of "Off" position.

In the structure disclosed by Figs. 5, 6 and 8 the valve 38 is provided with a different kind of controlling mechanism from that employed in Figs. 2, 3, 4 and 7. This latter controlling mechanism comprises a rotary button or knob 61 adapted to rotate in a vertical cylindrical opening 62 which is formed in the handle 32 in such manner that the upper end of the opening terminates in the upper surface of the handle while the lower end thereof communicates with the operating mechanism compartment 42. The position of the opening 62 with respect to compartment 42 is such that the forward end of the knob 61 is always directly above the upper end of the valve stem 44.

In order to hold the knob 61 in the opening 62 in such manner as to permit rotation thereof without vertical movement in the opening, the knob is provided with an integral outwardly projecting flange 63 adjacent the lower extremity thereof which is rotatably positioned in an annular groove 64 formed around the opening 62. The upper end of the knob 61 projects far enough above the upper surface of the handle that it can be clasped in the fingers and rotated within the opening 62. The lower end of the knob is provided with a variable cam surface indicated at 66 against which the upper end of the valve stem 44 is held by the spring 49. The formation of the cam surface 66 is such that when the knob 61 is in the position illustrated by Fig. 5 the valve 38 rests upon its seat, although it is possible for the valve to be opened against the pressure of the spring 49 by a sufficient difference in pressure between the suction compartment 18 and the discharge compartment 19. When the knob is in the position illustrated by Fig. 6 it is apparent that the valve 38 will be held in an open position at all times, although it is still possible for the valve to be opened to a greater extent in response to any unusually large difference in pressure between the suction compartment 18 and the discharge compartment 19.

It will be apparent that between the position in which knob 61 is shown in Fig. 5 and its position in Fig. 6 it will be possible to vary to any desired extent the position of the valve between these two extremes.

The possibility of making these various adjustments in the position of the valve 38 permits the operator to control manually or automatically, or both, the conditions under which air will flow through the conduit 33 into the suction compartment 18 and consequently makes it possible to provide sufficient cooling for the motor 27 under any of the various differential pressure conditions to which the compartments 18 and 19 may be subjected when the various suction and pressure tools with which tank cleaners may be provided are employed.

Also by varying the extent to which the valve 75 conduit for controlling the flow of air there-

38 may be automatically opened in response to the differential pressure between the suction and discharge compartments of the cleaner, it is possible to vary the amount of suction or pressure affecting the operation of any of the suction or pressure tools which may be employed with the cleaner.

While I have illustrated and described preferred embodiments of my invention, it is understood that these are capable of modification, and I therefore do not wish to be limited to the precise details set forth, but desire to avail myself of such changes and alterations as fall within the purview of the following claims.

I claim:

1. A tank cleaner comprising a casing having a motor, a fan and a dust separator arranged therein, a sealing means dividing said casing into suction and discharge compartments, said suction compartment having an air inlet thereto and said dust separator being arranged between said air inlet and said fan, said fan being arranged to pump air from said suction to said discharge compartment and to provide a pressure differential between said compartments, said motor being arranged in said casing to be cooled by said air pumped by said fan, a handle for moving said casing, said handle being provided with a conduit therein communicating with said suction compartment in said casing between said dust separator and said fan for supplying a limited amount of air to said suction compartment in addition to that supplied to said suction compartment through the air inlet thereof.

2. A tank cleaner comprising a casing having a motor, a fan and a dust separator arranged therein, sealing means dividing said casing into suction and discharge compartments, said suction compartment having an air inlet thereto and said dust separator being arranged between said air inlet and said fan, said fan being arranged to pump air from said suction to said discharge compartments and to provide a pressure differential between said compartments, said motor being arranged in said casing to be cooled by said air pumped by said fan, a handle for moving said casing, said handle being provided with a conduit therein connecting said suction and discharge compartments in said casing for supplying limited amounts of air to said suction compartment between said dust separator and said fan.

3. A tank cleaner comprising a casing having a motor, a fan and a dust separator arranged therein, sealing means dividing said casing into suction and discharge compartments, said suction compartment having an air inlet thereto and said dust separator being arranged between said air inlet and said fan, said fan being arranged to pump air from said suction to said discharge compartments, said motor being arranged in said casing to be cooled by said air pumped by said fan, said dust separator and air inlet being operatively associated with an air hose for the operation of various forms of cleaning tools employed by said cleaner, a handle for moving said casing, said handle being provided with a conduit therein communicating with said suction compartment on the downstream side of said dust separator in said casing for supplying air to said suction compartment for cooling said motor when the flow of air through said casing is reduced below the amount required for cooling said motor, and normally closed valve means associated with said conduit for controlling the flow of air there-

through, said valve means being constructed and arranged so as to be opened in response to a predetermined amount of suction within said suction compartment on the downstream side of said dust separator.

4. A tank cleaner comprising a casing having a motor, a fan and a dust separator arranged therein, sealing means dividing said casing into suction and discharge compartments, said suction compartment having an air inlet thereto and said dust separator being arranged between said air inlet and said fan, said fan being arranged to pump air from said suction to said discharge compartments, said motor being arranged in said casing to be cooled by said air pumped by said fan, said casing being provided with air inlet means communicating with said suction compartment in said casing on the downstream side of said dust separator for supplying air to said suction compartment for cooling said motor when the pressure in said suction compartment is reduced to an abnormally low value and normally closed valve means associated with said air inlet means for controlling the flow of air therethrough, said valve means being constructed and arranged so as to be opened in response to a predetermined amount of suction within said suction compartment on the downstream side of said dust separator.

5. A tank cleaner comprising a casing having a motor, a fan and a dust separator arranged therein, said casing having suction and discharge compartments, said suction compartment having an air inlet thereto and said dust separator being arranged between said air inlet and said fan, said fan being arranged to pump air from said suction to said discharge compartments, said motor being arranged in said casing to be cooled by said air, said casing being provided with air inlet means communicating with said suction compartment in said casing on the downstream side of said dust separator for supplying air to said suction compartment for cooling said motor when the flow of air through said separator is reduced below the amount required for cooling said motor and normally closed valve means associated with said air inlet means for controlling the flow of air therethrough, said air inlet means being constructed and arranged so that the maximum volume of air flow therethrough is relatively small as compared with that of said air inlet, said valve means being constructed and arranged so as to be opened in response to a predetermined amount of suction within said suction compartment on the downstream side of said dust separator.

6. A tank cleaner comprising a casing having a motor, a fan and a dust separator arranged therein, said casing being divided into suction and discharge compartments, said suction compartment having an air inlet thereto and said dust separator being arranged between said air inlet and said fan, said fan being arranged to pump air from said suction to said discharge compartments, said motor being arranged in said casing to be cooled by said air, said casing being provided with an air inlet means communicating with said suction compartment in said casing for supplying air to said suction compartment for cooling said motor when the flow of air through said separator is reduced below the amount required for cooling said motor, and a pressure actuated valve associated with said casing for controlling the flow of air through said air inlet means, said valve means being constructed and

arranged so as to be opened in response to a predetermined amount of suction within said suction compartment on the downstream side of said dust separator.

5 7. A tank cleaner comprising a casing having a motor, a fan and a dust separator arranged therein, said casing being divided into suction and discharge compartments, said suction compartment having an air inlet thereto and said dust separator being arranged between said air inlet and said fan, said fan being arranged to pump air from said suction to said discharge compartments, said motor being arranged in said casing to be cooled by said air, said casing being provided with air inlet means communicating with said suction compartment in said casing for supplying air to said suction compartment for cooling said motor when the flow of air through said separator is reduced below the amount required for cooling said motor, and a manually operated valve associated with said casing for controlling the flow of air through said air inlet means, said valve means being constructed and arranged so as to be opened in response to a predetermined amount of suction within said suction compartment on the downstream side of said dust separator.

8 8. A tank cleaner comprising a casing having a handle, a motor, a fan and a dust separator arranged therein, said casing being divided into suction and discharge compartments, said suction compartment having an air inlet thereto and said dust separator being arranged between said air inlet and said fan, said fan being arranged to pump air from said suction to said discharge compartments, said motor being arranged in said casing to be cooled by said air, said casing being provided with air inlet means communicating with said suction compartment in said casing for supplying air to said suction compartment for cooling said motor when the flow of air through said separator is reduced below the amount required for cooling said motor, a valve associated with said handle for controlling the flow of air through said air inlet means, and manually operated slide means for controlling said valve.

9 9. A tank cleaner comprising a casing having a handle, a motor, a fan and a dust separator arranged therein, said casing being divided into suction and discharge compartments, said suction compartment having an air inlet thereto and said dust separator being arranged between said air inlet and said fan, said fan being arranged to pump air from said suction to said discharge compartments, said motor being arranged in said casing to be cooled by said air, said casing being provided with air inlet means communicating with said suction compartment in said casing for supplying air to said suction compartment for cooling said motor when the flow of air through said separator is reduced below the amount required for cooling said motor, a valve associated with said handle for controlling the flow of air through said air inlet means, and rotary means for controlling said valve.

10 10. A tank cleaner comprising a casing having a motor, a fan, a suction compartment and a dust separator arranged therein, said suction compartment having an air inlet thereto and said dust separator being arranged between said air inlet and said fan, said fan being arranged to pump air out of said suction compartment, said motor being arranged to be cooled by said air, said casing being provided with air inlet
